UNITED STATES PATENT OFFICE

EMANUEL LEHMAN, OF RICHMOND, VIRGINIA

CHIN SUPPORT

Application filed August 25, 1931. Serial No. 559,815.

This invention relates to improvements in appliances used by embalmers for supporting the chin of a corpse, while the latter is being embalmed.

One object of the invention is to provide an appliance of this character that will be simple and inexpensive, and by which the mouth of the corpse will be held closed at all times during the embalming operation, regardless of whether or not the embalmer changes the position of the body by turning it on its side or the like.

A further object is to construct the appliance so that it may be readily disassembled when not in use, whereby it may be carried in a comparatively small kit bag.

A further object is to design the appliance so that the embalmer may use in connection therewith a device for holding the eyelids of a corpse closed. In other words, the eyelid device may or may not be used, its use being optional with the embalmer, and dependent upon the necessities of the case being treated.

A still further object is the provision of means for preventing accidental displacement of the movable parts of the appliance.

With these and other objects in view, the invention consists in certain details of construction and combinations and arrangements of parts, all as will hereinafter be more fully described and the novel features therof particularly pointed out in the appended claims.

In the accompanying drawing,

Figure 1 is a perspective view of the appliance, but with the eyelid depressors removed;

Fig. 2 is a side elevation;

Fig. 3 is an enlarged, detailed sectional view of the clutch mechanism for releasably retaining the head band carriers in any desired position on the frame;

Fig. 4 is a sectional view, longitudinally of one of the side members of the frame, illustrating the connection between the side member sections;

Fig. 5 is a similar view showing the side member sections detached;

Fig. 6 is a transverse section on the line 6-6 of Fig. 4; and

Fig. 7 is a detailed view of one of the eyelid depressors.

In the present device, there is a frame that consists essentially of side members and a lower cross member, carrying a chin rest 10 and head bands 11 that are slidable longitudinally of the sides of the frame. The chin rest 10 is mounted on the lower cross bar 12, the rest being preferably provided with a plurality of orifices 13 for the attachment of some suitable padding material. The side members are each preferably composed of lower and upper sections 14, 15, and are slidably engaged by carriers 16 on which the head bands 11 are pivotally secured. Displacement of the head band carriers 16 from the upper ends of the side members is prevented by an upper cross member 17. It will be appreciated that this accidental displacement of the carriers 16 could be prevented by other means, but the cross member 17 is preferred, as it lends rigidity to the frame.

Each carrier 16 is preferably of U-shape, the arms of the carriers being provided with apertures through which the sides of the frame extend. To retain the carriers in any position to which they may be adjusted on the frame sides, each carrier is provided with a plate 18 through which the sides of the frame extend, and each plate is loosely mounted at one end, in the carrier as at 19. At the other end of each plate, a spring 20 is interposed between the plate and an arm of the carrier so that the plate is normally urged away from the carrier arm, and assumes a position where it will bind or bite on the frame sides. However, the user of the appliance need only place one finger of each hand on the free ends of the plates 18, and press them toward the carrier arms by compressing the springs 20, under which circum-

stances the carriers are freely adjustable lengthwise of the frame. In order to further simplify the adjustment of the carriers 16 and the head bands, the carriers are connected by a cross bar 21, which insures the movement of the two carriers in unison with each other. In other words, both carriers are thus adjustable simultaneously and to identically the same extent, in either direction, so that the embalmer does not have to exercise any considerable care in order to insure the application of uniform pressure at both sides of the chin.

In accordance with the present invention, the side members, as before mentioned, are made sectional. This not only permits the upper and lower portions of the frame to be disassembled, so that they can be placed in a kit of comparatively small size, but it also permits the attachment of eyelid depressors on the frame sides. Preferably, the side sections 14, 15, of each side of the frame, are attached to one another by nuts 22, rotatably secured to the sections 14, the nuts being adapted to be screwed on to the threaded ends 23 of the upper side sections 15. The nuts 22 are, of course, of the same cross-section as the side sections proper, whereby they will not interfere with the movement of the carriers 16 on the frame. The eyelid depressors, as shown in Fig. 7, consist of finger-like depressor elements 24, attached to clamps 25, the clamps being formed with openings 26 for insertion of the sides of the frame, and with the usual clamping screws 27 for clamping the depressors in any desired position longitudinally of the frame sides. As will be apparent, when the device is not in use, it is disassembled simply by detaching the sections 14 of the sides from the sections 15, the carriers 16 remaining on the sections 15, as will be hereinafter described. When the embalmer is ready to use the appliance, he will attach the upper and lower portions of the frame, but if he desires to use the eyelid depressors, he will place them on the sides of the frame, before attaching the upper and lower portions together.

In order to prevent accidental displacement of the carriers 16 from the side member sections 15, when the frame is disassembled, the lower ends of the sections 15 are provided with spring elements 28 that project laterally from said section. When the two sections of the frame are disassembled, these spring members 28 will prevent displacement of the carriers 16, but when the frame is assembled, the nuts 22 will depress the spring members 28 below the surface of the side sections 15, as shown in Fig. 4, so that they will not interfere with the movement of the carriers 16.

What I claim is:

1. In a chin support for embalmers' use, a frame having a cross member and side

members, a chin rest on the cross member, head bands slidable on the side members, said side members being formed of detachable sections, and means at the ends of one section of each side member to prevent accidental displacement of the head bands, the retaining means at one end of each side member section consisting of a finger yieldingly projecting beyond the side surface of said section.

2. In a chin support for embalmers' use, a cross member, side member sections attached thereto, a chin rest on said cross member, a second cross member with side member sections connected thereto, means for detachably securing the side member sections of the two cross members together, and head bands slidable on said side members.

3. In a chin support for embalmers' use, a frame comprising side members each formed of a pair of sections, a cross member at each end of the side members, a chin rest on one of said cross members, a carrier slidably and frictionally engaged on each side member, head bands connected to said carriers, a cross bar connecting said carriers, means detachably securing the side member sections together, and means on one section of each side member for retaining said carriers thereon when the side members are disassembled.

4. In a chin support for embalmers' use, a frame composed of upper and lower cross members, a chin rest on the lower cross member, side sections on each cross member, the side sections of the upper cross member having threaded ends, spring fingers projecting laterally from said threaded ends, nuts rotatably secured in the side sections of the lower cross member, said nuts being adapted to be screwed on the ends of the side sections of the upper cross members and said fingers being depressed below the surface of the side sections by said nuts, and head bands slidably and frictionally engaging said side sections.

5. In a chin support for embalmers' use, a frame having a cross member, a chin rest on said cross member, side members extending from said cross member, each side member consisting of one section fixed to said cross member and a second section detachably secured to the fixed section, head bands slidable on the side members and means at the ends of the detachable side member sections for retaining the head bands thereon when said sections are detached.

EMANUEL LEHMAN.
